CONTINUOUS SEPARATOR

Arthur C. Bullen, San Francisco, Calif.

Application February 5, 1947, Serial No. 726,685

4 Claims. (Cl. 210—67)

1

My invention relates to a separator; and one of the objects of the invention is the provision of a truly continuous separator in which the machine while operating at its designed speed, continuously receives materials to be separated, and continuously and automatically ejects the separated parts of that material at different points. Another object of the invention is the provision of a continuous separator characterized by relatively low power requirements and high efficiency. Still another object of the invention is the provision of a continuous separator characterized by uniformity in the separation of materials fed to it. Still another object is the provision of a continuous separator in which improved means are provided for washing material passing through the machine.

The invention has other objects which will be explained in the following description of that form of the invention which is illustrated in the drawings. It is to be understood that the invention is not limited to this single embodiment, but may be included in a plurality of forms as set forth in the claims.

In the following description, my separator will be described in connection with the separation of molasses and sugar crystals from massecuite, for which purpose it was especially developed, but it may readily be used for the separation of other solids and liquids with no alteration or but little. A principal characteristic of my invention lies in the dual application of centrifugal force to a substantially cylindrical perforated drum into one end of which materials to be separated are fed. The drum is given a planetary rotation about a main or planetary axis and simultaneously is rotated about its own axis which lies at an angle to the planetary axis. The velocity of rotation of the drum about each axis, the relative values of these velocities, and the angle between the two axes provide variables by which the performance of the machine may be altered to conform to requirements in the separation of specific materials.

It is a well known fact that the application of centrifugal force, by rapidly rotating a cylindrical drum, as is the case in the standard centrifugal separators, forces the molasses out of the massecuite leaving the sugar crystals dry, the molasses passing through the small openings in the sides of the drum. The crystals cannot pass through the openings in the side of the drum and therefore are collected inside the separator. In the case of the standard cylindrical drum, the centrifugal force acts normally to the surface without any other component force, hence

2

the material to be worked must be injected while the separator is nearly at rest, then rotated rapidly until separation has taken place; and again brought to a near standstill in order to eject the charge. This process is not only very wasteful of time in the operation of the separator, but has the enormous disadvantage of requiring a very large initial force to give the separator a rapid acceleration. After separation is complete the separator has to be stopped quickly by the use of a powerful brake. This last operation is wasteful of energy and generally deteriorating to the machine.

In the case of a separator with a conical body 15 wherein the component of the centrifugal force which acts parallel to the surface of the cone is depended upon to move the sugar crystals along the surface and out of the basket, this force is insufficient to move all of the sugar out 20 of the basket, or it shears those crystals which are partially lodged in the perforations. This results either in eventual plugging of the perforations, necessitating stoppage for cleaning, or it produces a dull final product due to the shearing 25 of the crystals, and an increased crystal product in the molasses due to the small sheared crystal parts passing through the cone perforations with the molasses or wash liquor.

With my invention, I use two or more cylindrical perforated drums assembled in balanced order about and at an angle to the common planetary axis of rotation, instead of a single cylindrical or conical body as the usual practice is. Means are provided to rotate the bodies about 30 their own axes, and at the same time about the common axis of all the bodies. This dual revolution of the cylindrical drums sets at an angle to their common axis of rotation in my apparatus eliminates the disadvantages and waste commonly experienced in other separators.

The centrifugal force generated in my separator when in operation is distinctly dual in character and effect. Bodily rotation of the drums about the main or planetary axis tends to force 45 the materials outwardly from that axis; and of course rotation of each drum about its own axis tends to force the materials outwardly from its axis. Thus these two forces are constantly modifying each other, varying in a constant progression between a minimum which is their difference and a maximum which is their sum. Since the axes of the drums lie at an angle to the planetary axis, a component of the forces tends 50 to move the material through the drums to their ends farthest from the planetary axis.

Thus as massecuite is fed into the machine it

passes outwardly to the inner and upper ends of the drums and is then thrown to the outermost perforated wall of the drum, thus starting the separating process. As the rotation continues, an angular displacement of the massecuite from its original position takes place until its frictional resistance and adherence to the drum wall is overcome by the centrifugal force about the planetary axis, whereupon it is thrown away from the shell to a new position lower down in the drum.

Because of the viscous consistancy of the massecuite, the action as above described will not be in articulated action, but will result in a continuous rolling of the massecuite down the inside of the drum following a spiral course. Thus in my apparatus dual use of the centrifugal force is made: first, to separate the materials and secondly to move the retained solids automatically and continuously through the separating drum.

Another result of my arrangement of drums is to keep the cylinder perforations clean. When massecuite is first deposited against the outermost inside of the drum wall, the molasses is forced through the wall perforations, the sugar crystals being retained inside. When the drum has turned 180° on its axis, the centrifugal force from the common axis acts from the outside to the inside of the innermost side of the drum thus forcing any particles wedged in the perforations back into the drum and to the opposite side.

Another feature of my separator is the continuous and efficient application of wash water to the sugar crystals. In the standard separator the fairly thick wall of sugar crystals caught in the basket has to be over washed on the inside layers in order to properly wash the under or outside layers. This results in the partial dissolving of some of the sugar, and loss in efficiency. In my separator the rolling action of the sugar crystals passing the washing zone presents each layer of sugar to an equal wash, resulting in a smaller amount of wash water required and a more even and uniform washing of the sugar.

Still another feature of my separator is the continual discharge of the final dry sugar from the bottom of the drums, due to their turning on their own axes at an angle with their common or planetary axis, thus using the main centrifugal force to cause the retained material to travel in a spiral course continuously down the drums to discharge from their bottoms.

Referring to the drawings: Figure 1 is an elevation partly in vertical section, and showing the continuous separator of my invention. Figure 2 is a sectional view, the plane and conical surface in which the view is taken, being indicated by the line 2-2 of Figure 1. Figure 3 is another sectional view taken in a plane and conical surface indicated by the line 3-3 of Figure 1. Only one of the eight separating drum is shown.

Mounted rigidly on a suitable fixed support such as is provided by the structural steel members 2 and 3, is a housing 4, in which a vertical shaft 6 is journaled in suitable bearings 7. Keyed to the shaft is a pulley 8, connected by belts 9 to the pulley 12, fixed on the shaft 13 of the motor 14, which conveniently may be arranged on the supports 2-3.

Keyed to the main shaft 6 are two spiders 16 and 17 in which a series of separating drums 18 are journaled in balanced relation about the main shaft 6. At least two drums are necessary for balance and in the machine shown eight are

used. Each drum comprises a cylindrical shell pierced by small radially extending holes 19. The shell is wide open at the lower end, which is journaled in the lower spider 17 by a bearing 21 surrounding the shell. At the upper end the shell is provided with a stub shaft 22 journaled in bearings 23 in the upper spider 16.

An axial passage 24 extends up into the stub shaft past the middle of the bearing; and a series of transverse passages 26 through the shaft near the end of the axial passage, connects it at all times with an arcuate chamber 27, formed in the bearing face of the spider at the outer end of the radial passage 28. At its inner end, the passage is continued through the main shaft and into communication with the vertical feed passage 29 provided by the fixed feed tube 30 terminating at its upper end in a funnel 31. The feed tube is supported on a cap 32, fixed on the housing over the end of the main shaft; and extends downwardly through the hollowed upper half of the main shaft to open immediately into the radial passages, so that materials feed into the upper flared end of the tube emerge from the lower end and are whirled directly into the radial passages, with no opportunity to build up on the inside face of the shaft.

It is to be especially noted that the rotational axes 33 of the drums 18 lie at an angle to the rotational axis 34 of the main shaft. Important benefits flow from this angular relationship of the two rotational axes.

Means are provided for rotating each of the drums. Fixed on the upper end of each stub shaft is a bevel gear 36 in mesh with the central gear 37 fixed on the hub 38 of the pulley 39 journaled on the main shaft in bearings 41. The pulley 39 lies immediately below the pulley 8 and is driven by V-belts 42 from the lower end of the motor pulley 12. The relative sizes of the pulleys and gears are of course chosen to give the desired relative rotational speeds of the main shafts and drums. These relationships may vary for the efficient separation of different materials but for massecuite the proportions indicated in the drawings give excellent results.

Means are provided for introducing wash water or steam into the drums 18. Keyed to the main shaft 6 is a spider 46, each arm of which terminates in an arcuate saddle 47 in which a drum 18 lies. The saddle is formed with a chamber 48 extending over sufficient drum surface to cover a number of the apertures 19. Preferably the running joint between the drum and saddle is packed with a strip 49 of fibrous material to prevent leakage therethrough. The chamber 48 is connected, by passage 51 in the spider arm and main shaft, to the axial passage 52 in the lower end of the main shaft; and a fixed supply pipe 53 introduces water into the main shaft passage through a suitable gland and packing connection 54.

My separator is designed so that molasses is thrown off of the upper portion of each drum, the sugar crystals washed and the wash water thrown off in the mid portion, and the dry sugar crystals discharged from the open bottom end. A cylindrical curb or housing 56 concentric with the main shaft 6, and having a conical upper part 57, surrounds the lower part of the machine comprising the drums. An annular fin 58 is fixed on each drum at what may be considered the lower end of the zone from which the molasses will be thrown out; and immediately below the fin is the saddle 47, and the inwardly extending

cone top 59 of the curb 61, spaced inside and concentric with the outer curb. A third curb 62, concentric with the others, is arranged with its upper edge just above the orbit circle of the high side of the drum. The curb catches the discharging sugar crystals; and its insider vertical surface is swept by pitched blades 63, carried on a spider 64, journaled on a bracket 66. A pulley 67 on the hub of the spider is connected by belt 68 with a drive pulley on shaft 69; which in turn may be connected by belt 71, over suitable pulleys, to the motor shaft 13, or to an independent source of power.

Operation.—The machine being brought up to speed, massecuite is fed continuously into the funnel 31 and feed tube 30, through which it reaches the openings of the passages 28, where it is seized by centrifugal force and distributed equally through the connecting passages and into the tops of the drums 18. That portion of each drum above the fin separates the molasses from the massecuite, the former being thrown through the perforations and against the outside curb 57 from which it flows downwardly to be discharged from the machine through the annular passage 72. The fin 58 on the drum prevents creeping of the molasses down the outside of the drum wall. The algebraic sum of the centrifugal forces resulting from planetary rotation of the separating drum about the main axis 34, and that resulting from the bodily rotation of the drum about its own inclined axis 33 tends to move material in the drum in a downward spiral progression roughly indicated by the arrows 73.

Wash water is fed into the drum from the hollow saddle 47 where it is thrown against the separated crystals moving downwardly therein. The wash syrup passes through the perforations, and is thrown against the curb 59—61, flowing downwardly and out of the machine through the annular space 16. The lower part of the drums under the washing area around the spider 46, is the drying portion of the cylinder. The bearing case of the bearing 21 acts as a baffle to prevent wash syrup from creeping down inside the curb 62 to mix with the dry sugar crystals now working down the lower part of the drum to be discharged over the lower edge and against the curb 62 from which adhering crystals are dislodged by the blades 63.

Suitable means for separately collecting and disposing of the discharging molasses, wash syrup and sugar crystals are of course provided, but these form no part of my present invention and are not included in this description.

I claim:

1. A continuous separator comprising a shaft, means for rotating the shaft, a spider having passages therein and fixed on said shaft, stub shafts journaled in the spider at an angle with said first named shaft and having a passage therein in communication with the spider passages, a plurality of apertured drums axially aligned with and below the stub shafts and fixed thereon, the stub shaft passages opening into the upper ends of the drums and the lower end of the drums being open, a passage in the first named shaft opening at its upper end and in communication with the spider passages at its lower end, and means for rotating the stub shafts.

2. A continuous separator comprising a central shaft, an upper and lower spider fixed on the

central shaft, a plurality of apertured drums, each drum having an open lower end journaled in the lower spider for rotation about an axis inclined to the central shaft axis, a stub shaft extending axially from the upper end of each drum and journaled in the upper spider, said stub shaft having a passage opening into the drum, a passage in the central shaft, passages in the upper spider connecting the central shaft passage with the passage in the stub shaft, an intermediate spider fixed on the central shaft and extending to a running fit against the side of each drum, a chamber in the face of the intermediate spider against which the drum lies, a passage extending from each chamber through the intermediate spider and into the central shaft, a passage in the central shaft for supplying water to each of the intermediate spider passages, means for rotating the central shaft, and means for rotating the drums.

3. A continuous separator comprising a central shaft, means for rotating the shaft, a plurality of apertured drums journaled for rotation about an axis inclined to the shaft axis, means for rotating the drums about their axes, a spider fixed on the central shaft and having chambers therein opening against the sides of the drums, the edge of the spider surrounding the chamber forming a running fit with the drums, a passage extending from the chamber through the spider and into the central shaft, a passage in the central shaft in communication with the spider passage, means for introducing water into the shaft passage, and means for introducing materials to be separated into the drums at a point above said means for introducing water.

4. A continuous separator comprising a shaft, means for rotating the shaft, a spider fixed on the shaft intermediate the ends thereof, passages in the spider, a plurality of apertured drums open at their lower ends and having inlet passages at their upper ends directed down centrally into each drum and in communication with said spider passages, said drums being mounted on said spider for rotation about an axis inclined to the shaft axis, means for rotating the drums about their axes, a passage in the shaft running from the top thereof down to and communicating with said spider passages, and means for introducing material to be separated into the top of said shaft passage.
